POLYALKYLENEBISANILINE ANESTHETICS
Seymour L. Shapiro, Hastings on Hudson, and Louis Freedman, Bronxville, N.Y., assignors to U.S. Vitamin & Pharmaceutical Corporation, New York, N.Y., a corporation of Delaware
No Drawing. Filed June 18, 1958, Ser. No. 742,752
3 Claims. (Cl. 167—52)

This invention is concerned with certain N,N'-polymethylene bis(2,6-dimethylanilines) which are unusually effective anesthetic agents and with the process for their preparation.

Specifically, we have now found that compounds of the structure

wherein $n=3-5$, are potent anesthetic agents with desirable lack of toxicity.

If n is larger than 5 the anesthetic effect is considerably diminished, whereas replacement of the methyl groups by ethyl groups in the 2,6 positions of the aniline rings is also accompanied by diminished anesthetic effect. A further requisite for the structures within this system is that the nitrogen atoms have hydrogen groups attached. If these hydrogen atoms are replaced by methyl groups, anesthetic effect is reduced. Of particular significance is the stability of these active agents, with none of the groupings being vulnerable to hydrolysis.

The criticality in the structural requirements for pronounced anesthetic activity is manifest from Table I.

TABLE I

Anesthetic potency of polymethylene bis-anilines

R	R ₁	n	LD _{min.}	ED ₅₀ mg./ml.	Therapeutic Index
CH ₃	H	3	1,000	0.44	2,280
CH ₃	CH ₃	3	1,000	inactive	-----
C ₂ H ₅	H	3	1,000	inactive	-----
C ₂ H ₅	CH ₃	3	1,000	inactive	-----
CH ₃	H	5	1,000	0.84	2,940
CH ₃	CH ₃	5	1,000	12.0	83
C ₂ H ₅	H	5	1,000	>20.0	>50
CH ₃	CH ₃	4	1,000	inactive	>50
Xylocaine	---	---	225	6.8	33

The compounds were evaluated by the method of Chance and Lobstein, J. Pharmacol., 82, 203 (1944), for determining the median effective dose of a local anesthetic when applied to the cornea of a guinea pig eye.

A known concentration of solution of the local anesthetic is applied to both eyes of a guinea pig and the eyes kept bathed with this solution for two minutes. The eyes are then blotted to remove excess solution.

Five minutes later, the eyes are tested for the anesthetic effect. A horse hair mounted on a glass rod is used. The hair is pressed against the center of the cornea so that the hair is bent to about the same extent at each application. The hair is applied 10 times to each eye, and the process repeated 5 times for the test (total of 100 prods). The result is reported thus: 100 minus number of blinks=percent anesthesia.

Varying concentrations of the anesthetic agent are used and the percent anesthesia is plotted against concentration. The results are expressed as the ED₅₀ in mg./ml. which is the quantity of compound per milliliter of solution required to effect 50% anesthesia as established from the plot of concentration vs. percent anesthesia.

The toxicity of the individual compounds was established by administration subcutaneously (s.c.) to mice, in terms of the minimum dose required to be lethal to mice and expressed as LD_{min.} in milligrams of compound per kilogram of mouse.

The therapeutic index was then calculated by dividing the LD_{min.} by the ED₅₀, the result being a single figure embracing the anesthetic effectiveness of the compound and its inherent toxicity.

The selected compounds of this invention are bases and are desirably solubilized when used as their salts with strong acids such as hydrochloric, hydrobromic, sulfuric and the like.

The compounds of the type shown in Formula I where $n=3$ and 5 are conveniently prepared by the reaction of an excess of 2,6-dimethylaniline with the appropriate halide, suitably Br(CH₂)_nBr. The compound where $n=5$ has been reported by Sommers et al., J. Am. Chem. Soc., 75, 5280 (1953), with no indication of its utility as an anesthetic agent. However, the attempted preparation of the compound where $n=4$ could not be realized by this reaction since even in the presence of an excess of the 2,6-dimethylaniline, the reaction favored was apparently that where the compound cyclized as shown in the equation below.

For preparation of the required compound of type I, where $n=4$, it was necessary to prepare the N,N'-bis-succin-(2,6-dimethylanilide) and reduce this under forcing conditions with lithium aluminum hydride. Under such conditions only partial reduction occurred, the compound isolated being the (γ -[2,6-dimethylanilino]-butyr)-2,6-dimethylanilide. This in turn was isolated and upon treatment with lithium aluminum hydride yielded the compound I where $n=4$. These transformations are shown in the scheme I below.

The process and compounds of this invention will be more clearly understood from a consideration of the following specific examples which are given for the pur-

pose of illustration only and are not to be construed as limiting the scope of the invention in any way.

EXAMPLE 1

A mixture of 66.5 g. (0.55 mole) of 2,6-dimethylaniline and 22.2 g. (0.11 mole) of trimethylene dibromide was heated on the steam bath for 3 hours. When cool, the formed crystals were separated, rinsed with ether, dried and dissolved in 150 ml. of water. The aqueous solution was rendered alkaline by the addition of 6 N sodium hydroxide and the liberated base extracted with three 200-ml. portions of ether. The combined ether extracts were dried (anhydrous magnesium sulfate), filtered, the ether removed and the residue distilled. There was obtained 13.0 g. (50%) of N,N'-trimethylene-bis(2,6-dimethylaniline), B.P. 172-174° C. (0.2 mm.).

The product crystallized on standing, M.P. 71-73° C.

Analysis.—Calcd. for $C_{19}H_{26}N_2$: C, 80.8; H, 9.3; N, 9.9. Found: C, 81.1; H, 8.9; N, 10.0.

EXAMPLE 2

A solution of 9.3 g. (0.06 mole) of succinyl chloride in 60 ml. of ether was added gradually with stirring to a solution of 29.0 g. (0.24 mole) of 2,6-dimethylaniline in 200 ml. of ether. After the addition, stirring was continued for 40 minutes and the mixture of product and 2,6-dimethylaniline hydrochloride separated, washed with ether and then with water. The water-insoluble product N,N' - bis(2,6-dimethylphenyl)succinamide, 24.9 g. (90%), melted at 322-323° C. after recrystallization from methyl Cellosolve.

Analysis.—Calcd. for $C_{20}H_{24}N_2O_2$: C, 74.0; H, 7.5; N, 8.6. Found: C, 73.8; H, 6.9; N, 8.7.

There was similarly prepared from 2,6-dimethylaniline and malonyl chloride, N,N'-bis(2,6-dimethylphenyl)malonamide, M.P. 266-267° C.

Analysis.—Calcd. for $C_{19}H_{22}N_2O_2$: C, 73.5; H, 7.1; N, 9.0. Found: C, 73.1; H, 7.3; N, 8.9.

There was similarly prepared from 2,6-dimethylaniline and adipyl chloride, N,N'-bis(2,6-dimethylphenyl)adipamide, M.P. 290-292° C.

Analysis.—Calcd. for $C_{22}H_{28}N_2O_2$: C, 75.0; H, 8.0; N, 7.9. Found: C, 75.1; H, 8.2; N, 8.2.

EXAMPLE 3

(γ -[2,6-dimethylanilino]-butyr)-2,6-dimethylanilide was obtained as follows: A mixture of 4.56 g. (0.12 mole) of lithium aluminum hydride in 300 ml. of ether was stirred under reflux and 13.0 g. (0.04 mole) of N,N'-bis(2,6-dimethylphenyl)succinamide in 200 ml. of dioxane added. The reaction was maintained under reflux for 60 hours. After cautious addition of 2 ml. of water, 4.5 ml. of 40% sodium hydroxide was added and the reaction mixture stirred for 3 hours. Ether (400 ml.) was added and the residue separated and rinsed with two 300-ml. portions of ether. The combined filtrates were concentrated to about 25 ml. and on standing at 10° C., 5.9 g. (47.5%) of the product separated, M.P. 145-148° C., recrystallized (heptane) M.P. 149-150° C.

Analysis.—Calcd. for $C_{20}H_{26}N_2O$: C, 77.4; H, 8.4. Found: C, 77.5; H, 8.0.

EXAMPLE 4

5 N,N'-tetramethylene-bis(2,6-dimethylaniline) was obtained as follows: A mixture of 1.52 g. (0.04 mole) of lithium aluminum hydride in 300 ml. of ether was treated with a slurry of 4.65 g. (0.015 mole) of (γ -[2,6-dimethylanilino]-butyr)-2,6-dimethylanilide in 300 ml. of ether. After stirring under reflux for 30 hours and standing for an additional 90 hours, 1.0 ml. of water followed by 1.0 ml. of saturated sodium chloride and 2.25 ml. of 40% sodium hydroxide solution was added. The formed granular precipitate was separated, rinsed with ether and the combined ether filtrates concentrated. Unreacted anilide (2.4 g.) precipitated and was separated. The filtrate was evaporated to yield a residue which was distilled. There was obtained 1.11 g. (25%) of product boiling at 172-182° C. (0.11 mm.). On standing at room temperature the product crystallized, M.P. 61-63° C., recrystallized (pentane) M.P. 72-73° C.

Analysis.—Calcd. for $C_{28}H_{28}N_2$: C, 81.0; H, 9.5; N, 9.5. Found: C, 81.1; H, 9.4; N, 9.7.

It is to be understood that it is intended to cover all changes and modifications of the examples of the invention herein chosen for the purpose of illustration which do not constitute departure from the spirit and scope of the invention.

We claim:

30 1. A process for inducing anesthesia in a veterinary animal which comprises administering parenterally an effective amount of a compound of the formula

40 where n is an integer selected from the group consisting of 3 and 5, said compound being in unit dosage form.

2. The process of claim 1 where $n=3$.
3. The process of claim 1 where $n=5$.
